Des. 204,394
Patented Apr. 12, 1966

204,394

TOY ROBOT

Robert H. Wendt, Evanston, Ill.
(7566 Lincoln Ave., Skokie, Ill.)

Filed Oct. 4, 1965, Ser. No. 87,312

Term of patent 14 years

(Cl. D34—4)

FIG. 1 is a perspective view of a toy robot showing my new design;

FIG. 2 is a rear elevational view;

FIG. 3 is a side elevational view; and

FIG. 4 is a top plan view.

I claim:

The ornamental design for a toy robot, as shown.
